LADY'S STOCKING

Onesime H. Pons, Valdese, N. C., assignor to Pilot
Full Fashion Mills, Inc., Valdese, N. C., a cor-
poration of North Carolina

Application July 27, 1950, Serial No. 11,435

Term of patent 14 years

(Cl. D47—7)

To all whom it may concern:

Be it known that I, Onesime H. Pons, a citizen of the United States of America, residing at Valdese, in the county of Burke, State of North Carolina, have invented a new, original, and ornamental Design for a Lady's Stocking, of which the following is a specification, reference being had to the accompanying drawings, forming a part thereof.

Figure 1 is a side view of a stocking embodying my design;

Figure 2 is a rear elevation of a portion of the stocking as worn on a human leg.

The design is characterized by a reinforced high splice heel with the outer portion of the reinforcing yarn in the heel, sole and high splice portions being of the same color as the body yarn of the stocking and having a relatively

broad stripe extending on each side of the seam line and including the seam, reinforcing and seaming threads which is of a color contrasting to the body yarn and the high splice, sole and heel portions.

I claim:

The ornamental design for a lady's stocking, substantially as shown and described.

ONESIME H. PONS.
